(57) **CLAIM**

I claim the ornamental design for a headset accommodating cap, as shown and described.

DESCRIPTION

FIG. 1 is a perspective view of a headset accommodating cap according to the present invention;

FIG. 2 is a front view thereof;

FIG. 3 is a rear view thereof;

FIG. 4 is a top view thereof;

FIG. 5 is a bottom view thereof;

FIG. 6 is a first side view thereof; and,

FIG. 7 is a second, opposite side view thereof.

The broken lines along the surface of the headset accommodating cap depict stitching that forms no part of the claimed design.
